UNITED STATES PATENT OFFICE.

JOHN O. MCKEAN, OF WESTFIELD, MASSACHUSETTS, ASSIGNOR TO FOSTER MACHINE COMPANY, OF WESTFIELD, MASSACHUSETTS, A CORPORATION OF MASSACHUSETTS.

WINDING MACHINE.

Application filed October 27, 1925. Serial No. 65,149.

This invention relates to winding machines in which the yarn or thread may be wound into either conical or cylindrical packages as desired, said machine being commonly known as a cone and tube winder. In this type of machine it has heretofore been common to provide the cam which controls the reciprocating motion of the two traverse guides for the yarn or thread on opposite sides of the machine with three cam grooves, the two outer cam grooves being used when winding the conical packages or cones and the middle cam groove being used when winding cylindrical packages or tubes; it being understood that the cam grooves for cone winding are shaped differently from the cam groove for tube winding. An example of this type of machine is illustrated in United States Letters Patent No. 1,353,475, dated September 21st, 1920. This three groove cam necessitates the making of special traverse guides for each class of winding or traverse guides having removable and changeable cam groove shoes. It also necessitates the spacing of the winding units sufficiently far apart to accommodate the wide cams necessary to provide the three cam grooves therein.

The object of my invention is to provide means whereby the width of these traverse guide actuating cams may be materially lessened by utilizing a single cam groove, the opposite side walls of which are shaped to control the reciprocating movement of the traverse guide for cone winding when the cam is rotated in one direction and to control the reciprocating movement of the same traverse guide for tube winding when the cam is rotated in the opposite direction. This arrangement permits of a very great saving of space by allowing the winding units to be placed closer together than heretofore in this type of machine and also permits of a great saving in expense by eliminating the cutting of the two additional cam grooves in each cam. It also permits the use of a standard thread guide arranged in a common position for both classes of winding.

A practical embodiment of my invention is represented in the accompanying drawings, in which—

Fig. 1 represents in side elevation a portion of a winding machine at the drive end

thereof with my improved cams applied thereto.

Fig. 2 represents an end elevation with the drive arranged for cone winding.

Fig. 3 represents a similar view with the drive arranged for tube winding.

Fig. 4 represents a detail plan view showing the coaction of the cam and traverse guide for cone winding.

Fig. 5 represents a similar view showing the coaction of the cam and traverse guide for tube winding.

Fig. 6 represents a detail side view of the cam and traverse guide on a considerably enlarged scale.

Fig. 7 represents a cross section taken in the plane of the line VII—VII of Fig. 6.

Fig. 8 represents the lay-out of the cam groove.

The shaft 1 for each row of traverse guide actuating cams 2 is rotatably mounted in the machine frame and means are provided for rotating these cam shafts in one or the other direction, as follows:

The main drive shaft 3 herein shown as driven from an electric motor 4 carries a cone pulley 5 which drives, through a belt 6, an opposed cone pulley 7 carried by a shaft 8 suitably mounted in the machine frame. A gear 12 on the shaft 8 meshes with a gear 13 which also meshes with a gear 14, the two gears 13 and 14 being carried by an arm 9 rotatably adjustable on the hub of the shaft 8. The cam shafts 1 upon opposite sides of the machine are provided with intermeshing gears 15, 16. When it is desired to drive the cam shafts in the direction for cone winding, the arm 9 is rocked to bring the gear 13 into mesh with the gear 15 and when it is desired to drive the cam shafts in the opposite direction for tube winding, the arm 9 is rocked to bring the gear 14 into mesh with the gear 15, this movement bringing the gear 13 out of mesh with the gear 15, it still remaining in mesh with the gear 14.

The usual winding rolls 17 for the cones or tubes, along each side of the machine are carried by the shafts 18. One of the winding roll shafts 18 is driven from the drive shaft 3 through the pulley 19, belt 20 and pulley 21, while the other winding roll shaft 18 is driven from the drive shaft 3 through the

pulley 22, cross belt 23 and pulley 24. It will be understood that whether the machine is winding cones or tubes these shafts 18 will be driven continuously in one direction.

The traverse guides for the thread or yarn are denoted by 25, which guides reciprocate in the usual manner on the bars 26, 27. Each of these guides is provided with 10 a stud or roller 28, arranged to coact with a single circumferential cam groove 29 in its actuating cam 2, for cone or tube winding as follows:

The side walls of the cam groove 29 at 30 15 and 31 for one-half of the circumference of the cam are shown as substantially parallel and for the other half of the circumference the side walls at 32, 33 are shown as provided with progressively increasing 20 pitches in opposite directions: With the side walls of the cam groove thus shaped, when winding conical packages, the traverse guide will be accelerated when traveling toward the small end of the package for laying less yarn at the point of the package than at the base, causing it to gradually increase in taper as it builds up; and when winding cylindrical packages, the traverse guide acceleration is reversed on one-half of 25 the cam to neutralize the density of the winding for building up the package equally.

In other types of cone and tube winding, the shape of the side walls will be changed to suit.

35 It will be noted that the stud or roller 28 of the traverse guide at the opposite limits of its movement quite closely fits between the side walls of the cam grooves, thereby preventing pounding and ensuring the 40 proper throwing of the yarn at the ends of the package.

In operation:—When it is desired to wind a conical package, each cam 2 is driven in a direction which will cause the stud or 45 roller 28 of the traverse guide to travel along the side wall portions 33, 30 of the cam groove 29. When it is desired to wind a cylindrical package, the movement of the cam 2 is reversed, thus causing the stud or 50 roller 28 of the traverse guide to travel along the side wall portions 32, 31 of the cam groove 29.

In the present instance I have shown the 55 winding machine in Fig. 1 as provided with cone holders 34 and the parts arranged for cone winding. Of course when it is desired to wind tubes, suitable tube holders will be employed.

What I claim is:—

60 1. In a winding machine, a traverse guide for the thread or yarn, a guide actuating cam, and means for rotating it in either direction, said cam having only two circumferential cam faces arranged to control the 65 winding of conical or cylindrical packages

as the cam is rotated in one or the other direction.

2. In a winding machine, a winding drum, means for rotating it continuously in one direction, a traverse guide for the thread or 70 yarn, a guide actuating cam, and means for rotating it in either direction, said cam having only two circumferential cam faces arranged to control the winding of conical or cylindrical packages as the cam is rotated 75 in one or the other direction.

3. In a winding machine, a traverse guide for the thread or yarn, a guide actuating cam, and means for rotating it in either direction, said cam having a single circumferential groove for controlling the winding of conical or cylindrical packages as the cam is rotated in one or the other direction. 80

4. In a winding machine, a winding drum, means for rotating it continuously in one direction, a traverse guide for the thread or 85 yarn, a guide actuating cam, and means for rotating it in either direction, said cam having a single circumferential groove for controlling the winding of conical or cylindrical packages as the cam is rotated in one or the other direction. 90

5. In a winding machine, a traverse guide for the thread or yarn, a guide actuating cam, and means for rotating it in either direction, said cam having a single circumferential groove for controlling the winding of conical or cylindrical packages as the cam is rotated in one or the other direction, said 100 groove for one-half of the circumference having its side walls provided with different pitches. 105

6. In a winding machine, a traverse guide for the thread or yarn, a guide actuating cam, and means for rotating it in either direction, said cam having a single circumferential groove for controlling the winding of conical or cylindrical packages as the cam is rotated in one or the other direction, said 110 groove for one-half of the circumference having its side walls provided with different pitches and for the other half of the circumference having its side walls substantially parallel. 115

7. In a winding machine, a winding drum, means for rotating it continuously in one direction, a traverse guide for the thread or yarn, a guide actuating cam, and means for rotating it in either direction, said cam having a single circumferential groove for controlling the winding of conical or cylindrical packages as the cam is rotated in one or the other direction, said groove for one-half of the circumference having its side 120 walls provided with different pitches. 125

8. In a winding machine, a winding drum, means for rotating it continuously in one direction, a traverse guide for the thread or yarn, a guide actuating cam, and means for rotating it in either direction, said cam 130

having a single circumferential groove for controlling the winding of conical or cylindrical packages as the cam is rotated in one or the other direction, said groove for one-half of the circumference having its side walls provided with different pitches and for the other half of the circumference having its side walls substantially parallel.

9. In a winding machine, a traverse guide for the thread or yarn, a guide actuating cam, and means for rotating it in either direction, said cam having a single circumferential groove for controlling the winding of conical or cylindrical packages as the cam is rotated in one or the other direction, said groove for one-half of the circumference having its side walls provided with progressively increasing pitches in opposite directions.

10. In a winding machine, a traverse guide for the thread or yarn, a guide actuating cam, and means for rotating it in either direction, said cam having a single circumferential groove for controlling the winding of conical or cylindrical packages as the cam is rotated in one or the other direction, said groove for one-half of the circumference having its side walls provided with progressively increasing pitches in opposite directions and for the other half of the circumference having its side walls substantially parallel.

11. In a winding machine, a winding drum, means for rotating it continuously in one direction, a traverse guide for the thread or yarn, a guide actuating cam, and means for rotating it in either direction, said cam having a single circumferential groove for controlling the winding of conical or cylindrical packages as the cam is rotated in one or the other direction, said groove for one-half of the circumference having its side walls provided with progressively increasing pitches in opposite directions.

sively increasing pitches in opposite directions.

12. In a winding machine, a winding drum, means for rotating it continuously in one direction, a traverse guide for the thread or yarn, a guide actuating cam, and means for rotating it in either direction, said cam having a single circumferential groove for controlling the winding of conical or cylindrical packages as the cam is rotated in one or the other direction, said groove for one-half of the circumference having its side walls provided with progressively increasing pitches in opposite directions and for the other half of the circumference having its side walls substantially parallel.

13. In a winding machine, a traverse guide for the thread or yarn, a guide actuating cam, and means for rotating it in either direction, said cam having a single circumferential groove, the side walls of which are so shaped that when the cam is driven in one direction the guide is reciprocated to wind conical packages and when the cam is driven in the opposite direction the guide is reciprocated to wind cylindrical packages.

14. In a winding machine, a winding drum, means for rotating it continuously in one direction, a traverse guide for the thread or yarn, a guide actuating cam, and means for rotating it in either direction, said cam having a single circumferential groove, the side walls of which are so shaped that when the cam is driven in one direction the guide is reciprocated to wind conical packages and when the cam is driven in the opposite direction the guide is reciprocated to wind cylindrical packages.

In testimony, that I claim the foregoing as my invention, I have signed my name this 22nd day of Oct., 1925.

JOHN O. MCKEAN.
